COPY HOLDER

Phoebe C. Baughan, Dillard, Ga.

Application January 22, 1937, Serial No. 121,883

7 Claims. (Cl. 120—32)

This invention relates to a copy-holder.

An object of the invention is the provision of a copy-holder which may be supported upon a desk of a typist whereby the typist may move the copy progressively as the work of typing is being completed and the line to be copied will always be in position where it can be readily seen.

Another object of the invention is the provision of a copy-holder which may carry small or large sheets and in a position where visibility will be at its best and where the copy-holder can be readily manipulated for the convenience of the typist.

A further object of the invention is the provision of a copy-holder for carrying copies on ordinary sheets of paper but the copy-holder may be extended readily and conveniently to carry sheets of approximately twice the size, or more, of the ordinary sheet of paper.

A still further object of the invention is the provision of a copy-holder for progressively moving printed or typed matter into view and for retaining the matter in a position for convenient inspection by the typist, the device being so constructed that the sheet of printed matter may be progressively moved without any inconvenience to the operator.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Figure 1 is a view in perspective of a copy-holder constructed in accordance with the principles of my invention.

Figure 2 is a transverse vertical view taken along the line 2—2 of Figure 1.

Figure 3 is a horizontal section taken along the line 3—3 of Figure 2.

Figure 4 is a horizontal section taken along the line 4—4 of Figure 2.

Figure 5 is an enlarged fragmentary end elevation of the operating device for the driven rollers of the copy-holder.

Figure 6 is a similar view to Fig. 5 showing an end elevation of the operating means adjusted for the line-for-line movement of close spacing of the lines.

Figure 7 is a plan view of the operating means shown in Figs. 5 and 6.

Figure 8 is a horizontal section taken along the line 8—8 of Figure 5.

Figure 9 is a view in elevation of the device controlling the throw of the operating pawl of the actuating mechanism for the roller, and

Figure 10 is a horizontal section taken along the line 10—10 of Figure 1.

Referring more particularly to the drawings, 15 designates a base member of a U-shaped frame 16 having upstanding legs 17 and 18. Secured to the frame or formed integrally therewith is an extension or foot 19 projecting forwardly of the base member 15. A pair of lateral extensions 20 and 21 are secured in any approved manner to the base member 15 and extend forward of the frame 16 and are provided with rubber feet 22 adapted to rest upon the top of the desk. It will be noted that the extensions 20 and 21 are offset as shown at 23 for raising said extensions above the desk so that the feet 22 and the base member 15 will support the U-shaped frame 16. The typewriter (not shown) is placed on the extensions.

Bars or standards 25 and 26 each have a slot 27 which receives a thumb screw 28 which is threaded into an opening 29 in the legs 17 and 18 of the frame 16. This permits vertical adjustment of the bars 25 and 26 for a purpose which will be presently explained.

A spacer rod 30 is connected at 31 to the upper ends of the bars 25 and 26 and not only maintains these bars in their respective parallel positions but provides a means for guiding the copy outwardly from the frame when said copy has been moved by rollers 32 and 33.

The pressure roller 32 is provided with a shaft 34 and the ends of this shaft are rotatably mounted in arms 35. These arms are carried by the upper end of a U-shaped bracket, generally designated by the numeral 36, and consists of a base member or rod 37, side arms 38 and pintles 39 pivotally mounted at 40 in ears 41 extending laterally or forwardly of the frame 16. A coil spring 42 is connected to the ear 41 at one end while the opposite end is connected to the shaft or base member 37. It will be noted that there are two springs 42, one at each end of the base member or surrounding the pintles 39 and tend always to urge the bracket 36 and likewise the roller 32 outwardly so that said roller will be in contact with the driven roller 33.

Each of the arms 35 is provided at its lower end with a reduced portion 43 adapted to be received within a passage 44 in the upper end of the arm 38. A thumb screw 45 threaded into an

opening in a collar 46 at the upper end of each arm 38 is adapted to engage the reduced portion 43 for securing said reduced portions in predetermined positions as may be desired. In other words, when the pressure roller is raised the thumb screw 28 is released and the bars 25 and 26 are elevated to the proper height. Then the set screws 45 are released so that the arms 35 may be elevated to properly position the pressure roller 32 with respect to the driven roller 33.

The driven roller 33 has a shaft 47 extending entirely through the roller and secured thereto. The ends of the shaft project beyond the ends of the roller. It will be noted that the end 48 (Fig. 4) of said shaft extends beyond the bar or standard 25 and has a bearing at 49 while the opposite end of the shaft 47 has a similar bearing 50 in the bar 26. A shoulder 51 on the roller 33 abuts the inner face of the bar 26.

A manipulating knob 55 is secured in any approved manner to the shaft 47 at its outer end so that rotation of the knob will cause rotation of the shaft 47 and likewise the roller 33.

Referring more particularly to Figs. 1 and 5 to 9, inclusive, it will be seen that mechanism is provided whereby the roller 33 may be rotated by the member 55 or by means of a lever 56 pivoted at 57 on a shaft carried by a block 58 mounted on the member 19 at the bottom of the device. A spring 59, through its connection between the lever 56 and the block 58, tends to move one end of the lever in a downward direction towards the member 19. The end of the lever which has the finger-piece 60 will be moved in the opposite direction or upwardly from the desk or support for the frame 16. A lip 61 on the member 21 prevents the typewriter from being placed too close to the lever 56 and aids in retaining the typewriter in place.

A link 62 is pivotally connected at 63 with the inner end of the lever 56 and is provided with an internal passage 64 at its upper end to receive an extensible link 65. A thumb screw 66 carried by an enlargement 67 at the upper end of the link 62 is adapted to secure the link 65 to the link 62 when said links have been adjusted relative to each other. This adjustment is particularly advantageous when the bars 25, 26 and the arms 35 are elevated or adjusted to a higher position for raising simultaneously the driven roller 33 and the pressure roller 32.

Referring more particularly to Figs. 5 to 9, inclusive, it will be seen that a device is employed which will progressively revolve the roller 33 through predetermined arcs and the arc through which the roller is revolved will depend upon the semi-circular member 70 which is carried by a plate 71 having an opening 72 and the finger pieces 73 and 74. A ratchet wheel 75 has a sleeve 76 received by the shaft 47 and the outer end of the sleeve is provided with projections or keys 77 adapted to be received within diametrically disposed notches 78 in a sleeve 79 secured to the knob 55. The sleeve 76 and likewise the ratchet wheel 75 are loose on the shaft 47 but the sleeve 79 is secured to the shaft 47 by means of a set screw 80 so that when the knob 55 is rotated the ratchet wheel 76 will likewise be rotated.

A pawl 81 is secured at 82 to a lever 83 which is pivotally mounted at 84 on the shaft 47 and the link 65 is pivotally connected at 85 to the lever 83, so that when the link 65 is moved vertically upwardly the lever will be raised and the free end of the pawl 81 will ride over the curved

surface of the member 70 until it slips beyond the free edge 70a of the member 79 and engages one of the teeth 75a of the ratchet wheel 75. The free end of the pawl 81 at all times will be in contact with the curved outer surface of the member 70 before it engages a tooth.

The lever 83 is offset as shown at 86 so that it will clear the member 70 and a washer 87 is disposed between the lever 83 and the pawl 81 where said pawl is connected to the lever 83.

As shown more particularly in Fig. 8 the manipulating plate 71 is offset from the plane of the member 70 and is spaced from the inner face of the ratchet wheel 75 by means of the pivoted end 84 of the lever 83 and a washer 88. The plate 71 is located between the washer 88 and a washer 89 on the shaft 47 with the washer 89 in flat engagement with the bar or extension 26. A coil spring 87a in washer 87 pulls the pawl 81 downwardly so that when said pawl rides beyond the point 70a it will engage the teeth 75a.

A spring arm 90 is secured at 91 to the bar or extension 26 and extends downwardly therefrom and is provided with a roller 92 adapted to engage between the teeth 75a of the wheel 75. A second spring member 93 is secured to the spring member 90 and extends laterally at its lower end from the roller 92 and is provided with a detent 94 adapted to engage within notches 95 at the periphery of the operating plate 71 for retaining said plate in a predetermined position.

A second extension driven roller 100, as shown more particularly in Figure 4, has a sleeve 101 secured thereto by a set screw 102a and adapted to receive the projecting end 48 of the shaft 47 and is secured to said shaft by means of a set screw 102. From the opposite end of the roller projects a shaft 103 which is received within a bearing 104 at the upper end of a bearing plate 105 carried by an extensible arm or rod 106. The outer end of the shaft 103 is threaded, as shown at 107, to receive the nut 108 and lock nut 109, for retaining the shaft and likewise the roller 100 in position.

The extensible arm 106 is received within a standard 110 having a base plate 111. A collar 112 is carried by the upper end of the standard 110 and a thumb screw 113 secures the rod 106 in any of its adjusted positions within the standard 110.

The bar 105 is also provided with a bearing 115 to receive the free end of a shaft 116 which carries a second pressure roller 117. This pressure roller is adapted to be maintained in coacting relation with the driven roller 100 at all times. The shaft 34 of the pressure roller 32 is provided with an internally threaded sleeve 118 into which is threaded, as shown at 119, the inner end of the shaft 116, whereby said shaft is connected to the shaft 34 so that the pressure rollers 32 and 117 will be simultaneously revolved.

It will be seen by the above construction that the auxiliary driven roller 100 and the auxiliary pressure roller 117 may be readily removed or disconnected from the respective rollers 33 and 32 in an easy manner and the standard 110 may also be removed when it is desired to hold copy sheets having a predetermined width. However, when the sheets are too large for the single copy-holder with the two rollers 32 and 33 the rollers 117 and 100 are respectively connected to the rollers 32 and 33 readily so that when the U-shaped bracket 36 is swung slightly outwardly the rollers 32 and 117 will move about the pivot point of the shaft 116 in the bearing 75

115 as well as about pivot rod 37. This bearing, however, has a slightly larger opening than the diameter of the shaft 116 so that the combined rollers 32 and 117 may be swung outwardly with the bearing 115 acting as a pivot.

5 If the copy is sufficiently large or long it is only necessary to release the thumb screws 28, 45, 66, and 113 whence all of the rollers together with the operating mechanism for the driven roller 33 may be elevated to the height desired, after which the thumb screws are reset.

10 The bracket 36 has its lower end disposed outwardly from the inner edge of the members 17 and 18 so that the copy paper may be placed to its full length to the bottom of the frame 16.

15 When the operator desires to move the copy to another line for typing, it is only necessary to press down upon the member 60 for operating the lever 56 whence the rod 65 will be elevated, causing the pawl 81 to ride over the semi-circular member 70 until it slips off the free edge 70^a and engages between a pair of the teeth 75^a of the ratchet wheel 75 and since said pawl is moving to the right in Figs. 5 and 6 it will partially rotate the ratchet wheel and likewise the roller 33 and the roller 100 when said last-mentioned roller is attached to the roller 33.

20 In the position of the semi-circular member 70 in Fig. 5 the pawl will rapidly slip off the free edge 70^a of the member 70 and engage the teeth for moving the ratchet wheel through a greater arc than it will do with the member 70 in the position shown in Fig. 6. In other words, if it is necessary to move the ratchet wheel 75 25 through an angle between the edges of a pair of teeth to bring the next line of printing into view the member 71 is partially rotated until the free edge 70^a passes beyond the free end of the pawl 71 sufficiently to prevent the pawl from engaging the teeth through a predetermined movement of the pawl until it comes to a position where it will move the ratchet wheel through the smallest angle. If a greater angle of movement of the ratchet wheel is desired the plate 35 40 45 50 55 71 is moved in a counter-clockwise direction in Fig. 6 a tooth or so so that the free edge 70^a will permit the pawl 81 to move the ratchet wheel 75 through an angle between two pairs of teeth. The plate 71 may be further rotated in the counter-clockwise direction in Fig. 6 so that the ratchet wheel 75 will be moved through a greater angle by permitting the free end of the pawl to slip off the free end of the member 70 during an earlier period of movement of said pawl.

The shafts 34 and 116 extend entirely through the pressure rollers 32 and 117, respectively, to maintain an even pressure throughout the length of said rollers. The shafts 47 and 103 extend 60 through the respective rollers 33 and 100 to give stability to said rollers.

I claim:

1. A copy-holder comprising a frame, a driven roller on the frame, means for rotating the driven roller, a shaft having an extension projecting from the roller and beyond the frame, a second roller having removable connections at one end thereof with the extension on the shaft, a standard for supporting the other end of the second roller, pressure rollers associated with the first-mentioned rollers, one of said pressure rollers being supported from the frame and the other pressure roller being supported by the standard and the pressure roller which cooperates with the driven roller.

2. A copy-holder comprising a frame, a driven roller on the frame, means for rotating the driven roller, a shaft having an extension projecting from the roller and beyond the frame, a second roller having removable connections at one end thereof with the extension on the shaft, a standard for supporting the other end of the second roller, pressure rollers associated with the first-mentioned rollers, one of said pressure rollers being supported from the frame and the other pressure roller being supported by the standard and the pressure roller which cooperates with the driven roller, the pressure rollers having removable connections for simultaneous operation.

3. A copy-holder comprising a frame, a driven roller on the frame, means for rotating the driven roller, a shaft having an extension projecting from the roller and beyond the frame, a second roller having removable connections at one end thereof with the extension on the shaft, a standard for supporting the other end of the second roller, pressure rollers associated with the first-mentioned rollers, one of said pressure rollers being supported from the frame and the other pressure roller being supported by the standard and the pressure roller which cooperates with the driven roller, said standard and frame having extensible portions for raising bodily and simultaneously the driven and pressure rollers.

4. A copy-holder comprising a frame, a driven roller mounted on the upper end of the frame, a U-shaped bracket pivoted to the lower end of said frame, a pressure roller mounted for rotation in the upper end of the bracket, a resilient means for retaining the pressure roller in co-acting relation with the driven roller, a second driven roller removably connected at one end to the first driven roller, a standard supporting the other end of the second driven roller, a second pressure roller removably connected at one end with the first pressure roller and removably supported at the other end by the standard.

5. A copy-holder comprising a frame, a driven roller mounted on the upper end of the frame, a U-shaped bracket pivoted to the lower end of said frame, a pressure roller mounted for rotation in the upper end of the bracket, a resilient means pressing the bracket for retaining the pressure roller in co-acting relation with the driven roller, a second driven roller removably connected at one end to the first driven roller, a standard supporting the other end of the second driven roller, a second pressure roller removably connected at one end with the first pressure roller and removably supported at the other end by the standard, the combined pressure rollers being resiliently mounted by means of the standard and the spring-pressed bracket.

6. A copy-holder comprising a frame, a standard spaced from the frame, a pair of driven rollers carried by the frame and standard, said rollers being in longitudinal alignment and having their adjacent ends removably connected together, a bracket pivotally connected at its lower end to the lower end of the frame, a pair of pressure rollers having the adjacent ends removably connected together and supported by the standard and bracket, said bracket being spaced outwardly of the frame for substantially the full length of said frame and bracket.

7. A copy-holder comprising a frame, a standard spaced from the frame, a pair of driven rollers carried by the frame and standard, said rollers being in longitudinal alignment and having their adjacent ends removably connected together, a

bracket pivotally connected at its lower end to the lower end of the frame, a pair of pressure rollers having the adjacent ends removably connected together and supported by the standard and bracket, said bracket being spaced outwardly of the frame for substantially the full length of

said frame and bracket, means for mounting one end of a pressure roller on the standard to permit pivotal movement of the combined pressure rollers when the bracket is moved outwardly from the frame.

PHOEBE C. BAUGHAN.
